Specification for Design.

Patented May 18, 1920.

Application filed November 28, 1919. Serial No. 341,320. Term of patent 7 years.

To all whom it may concern:

Be it known that I, ALFRED G. KINTZ, a citizen of the United States, residing at Wallingford, in the county of New Haven and State of Connecticut, have invented a new, original, and ornamental Design for a Spoon, Fork, or Similar Article, of which the following is a specification, reference being had to the accompanying drawing, forming part thereof.

Figure 1 is a face view of a spoon, fork, or similar article, showing my new design.

Fig. 2 is a side view of the same.

Fig. 3 is a sectional view on the line 3—3 of Fig. 1.

I claim:

The ornamental design for a spoon, fork or similar article, as shown.

ALFRED G. KINTZ.
